UNITED STATES PATENT OFFICE

156,467

ELECTRIC FRANKFURTER COOKER

Mitchell W. Thomas, Chicago, Ill.

Application January 14, 1949, Serial No. 230

Term of patent 14 years

(Cl. D81—10)

To all whom it may concern:

Be it known that I, Mitchell W. Thomas, a citizen of the United States, residing at Chicago, in the county of Cook and State of Illinois, have invented a new, original, and ornamental Design for an Electric Frankfurter Cooker, of which the following is a specification.

In the accompanying drawings:

Fig. 1 is a perspective view of an electric frankfurter cooker embodying my new design; and

Fig. 2 is a front elevation thereof with the cord and plug omitted for convenience of illustration.

The dominant features of my design reside in the portions shown in full lines.

I claim:

The ornamental design for an electric frankfurter cooker, substantially as shown and described.

MITCHELL W. THOMAS.
